UNITED STATES PATENT OFFICE.

SAMUEL B. FOWLER, OF NEW YORK, N. Y.

ANNUNCIATOR.

SPECIFICATION forming part of Letters Patent No. 620,577, dated March 7, 1899.

Application filed October 25, 1898. Serial No. 694,610. (No model.)

To all whom it may concern:

Be it known that I, SAMUEL B. FOWLER, a citizen of the United States, residing in New York, (Tarrytown,) in the county of West-
5 chester, State of New York, have invented certain new and useful Improvements in Annun-
ciators, of which the following is a speci-
fication, reference being had to the accom-
panying drawings, forming a part hereof.

10 This invention relates to electric annun-
ciators, and more especially to the annun-
ciators employed in telephone systems to indi-
cate to the operator at the exchange the num-
ber of the subscriber who calls.

15 One object is to make it practicable to em-
ploy illuminated drops which will quickly
catch the eye of the operator without the ex-
pense and unreliability incident to the use of
a small electric lamp for each drop.

20 Another object is to simplify the construc-
tion and arrangement of telephone annun-
ciator-boards and to reduce the cost of main-
tenance.

The invention is illustrated in a convenient
25 and practical form, with several different ar-
rangements of the electrical connections, in
the accompanying drawings, in which—

Figure 1 is a front view of a portion of an
annunciator-board to which the improve-
30 ments are applied. Fig. 2 is a vertical trans-
verse section of the same. Fig. 3 is a longi-
tudinal section, on a larger scale, of one of
the annunciator-tubes. Fig. 4 is a detail view,
35 in horizontal section, on a plane indicated by
the line 4 4 of Fig. 3, but on a larger scale.
Figs. 5 and 6 are diagrammatic views repre-
senting electrical connections which pertain
as the source of illumination, two different
40 arrangements being indicated. Fig. 7 is a
similar view representing the electrical con-
nections when a continuously-lighted lamp is
used.

The improvements which constitute the
45 subject-matter of this invention, considered
apart from the source of illumination, are ca-
pable of use either with a lamp which is con-
tinuously lighted or with a lamp which is
lighted at each call, the lamp in the former
50 case being either electric or oil or gas, and
the lamp in the latter case being electric.

The source of illumination, moreover, of what-
ever kind, may obviously be so located with
reference to the drops as to effect their illu-
mination either directly or by means of re-
55 flectors. In the drawings, however, in which
is represented an arrangement which gives
satisfactory results in practice, the source of
illumination or lamp is shown as an electric
lamp A, situated in rear of the drops, so that
60 the light shall shine through the same from
the rear. In the arrangements of electrical
connections shown in Figs. 5 and 6 the lamp
A is not continuously lighted, but is lighted
at each call, while for the arrangement shown
65 in Fig. 7 the lamp (not shown in said figure)
would be continuously lighted. In either
case a single lamp A illuminates a large num-
ber of drops, a few only being shown in the
drawings.

70 The board B is supported or arranged in
any usual or suitable manner and carries the
usual jacks C, by means of which and the
usual plugs (not shown) the desired connec-
tions between different subscribers are ef-
75 fected. The "drops," so called, correspond-
ing to the several jacks and electrically con-
nected with each subscriber, as usual, are
indicated at D. As shown, each drop con-
sists of a tube d, about which is wound a coil
80 of wire d', which is in circuit with the sub-
scriber's instrument. Secured to the tube d
is a sleeve or collar d'', of insulated material,
which furnishes a convenient support for a
balanced shutter d³, which is slightly over-
85 weighted or otherwise caused to stand nor-
mally across the tube, excluding the light
therefrom. The shutter is wholly or partly
of iron or other magnetic material, but at any
rate has in its construction so much of mag-
90 netic material that it is subject to the effect
of the current which passes about the tube d
and in the field of which the shutter stands
and will be deflected like the needle of a gal-
vanometer from its normal position when cur-
95 rent passes through the coil d' and will be
caused to stand in a plane parallel with the
axis of the tube, thus permitting the light to
pass through the tube. Under ordinary con-
ditions the shutter will vibrate or flutter for
100 a time before it comes to rest, thus alternately
permitting and cutting off the passage of

light, and thereby more surely attracting the attention of the operator. At the front end of the tube a suitable cap d^4 supports a piece of ground glass d^5 , upon which is painted the 5 subscriber's number, this ground-glass screen being illuminated in the manner already described. The location of the shutter between the screen and the lamp saves the necessity of having any mechanism on the front of the 10 board and makes the whole construction more compact, besides saving considerable expense. A suitable reflector E may be employed in connection with the lamp A, if necessary, to distribute the light more uniformly 15 to the various drops which are intended to be illuminated from the same source.

In some cases it is preferable to have the lamp A lighted as each call comes in rather than to have it lighted continuously. In such 20 cases the lamp will of course be included in a local circuit, (indicated at a .) such local circuit having a switch a' , which is normally open, but is adapted to complete the local circuit when acted upon by a relay R, which is 25 included in the circuit with the coil d' of the drop. This relay R is common to all of the drops illuminated by the lamp A. As indicated in Fig. 5, it may be arranged in multiple with the several drop-coils d' , or, as represented in Fig. 6, it may be arranged in series therewith. If an oil or other continuously-lighted lamp is used, the local circuit and relay may be dispensed with, as indicated in Fig. 7.

35 The connections between each subscriber and the exchange may be arranged as usual and are not necessary to be described in detail herein, a subscriber's circuit being indicated at S in Fig. 5, the connections between 40 the same and the drop being established through the jack C in the usual manner. It may be added that in the multiple arrangement represented in Fig. 5 the resistance of each coil d' is so proportioned to the resistance of the relay R that the current will divide, sufficient passing over the coil to operate the shutter and the remainder passing over the relay to close the lamp-circuit.

It will be obvious that various modifications 50 can be made without departing from the spirit of the invention and that the invention therefore is not to be restricted to the precise construction and arrangement shown and described herein.

55 I claim as my invention—

1. An annunciator-drop comprising a tube, a coil about said tube and adapted to be included in an electrical circuit and a balanced shutter of magnetic material supported in the 60 field of said coil.

2. In an annunciator, the combination with a source of light, of a tube having a light-screen at one end, a coil of wire about said tube adapted to be included in an electrical circuit, and a balanced shutter of magnetic material supported in the field of said coil.

3. An annunciator comprising a coil adapted to be included in an electrical circuit and having an axial opening for the passage of light, a source of light to illuminate said opening, and a shutter of magnetic material hung within the field of said coil and normally closing the axial opening of the coil, whereby when current is passed through said coil the shutter is moved by the influence of the current in said coil to permit the passage of light through said opening. 70

4. An annunciator comprising a coil adapted to be included in an electrical circuit and having an opening for the passage of light, a light-screen in said opening, a source of light to illuminate said screen, and a shutter of magnetic material hung within the field of said coil, whereby when current is passed through said coil the shutter is moved by the influence of the current in said coil to permit the passage of light to said screen. 80

5. In an annunciator, the combination with a source of light, of a tube open for the passage of light therethrough, a coil of wire about said tube adapted to be included in an electrical circuit, and a shutter of magnetic material hung within the field of said coil and normally closing the opening through said tube, whereby when current is passed through 95 said coil the shutter is moved by the influence of the current in said coil to permit the passage of light through said tube.

6. In an annunciator, the combination with a source of light, of a tube open for the passage of light therethrough, a light-screen at one end of said tube, a coil of wire about said tube adapted to be included in an electrical circuit, and a shutter of magnetic material hung within the field of said coil and normally closing the opening through said tube, whereby when current is passed through 100 said coil the shutter is moved by the influence of the current in said coil to permit the passage of light through said tube upon said screen. 105

7. An annunciator-board comprising a series of coils adapted to be included in electrical circuits and having each an axial opening for the passage of light, a common source of light to illuminate all of said openings, and 115 a shutter of magnetic material hung within the field of each of said coils and normally closing the axial opening of said coil, whereby when current is passed through said coil the shutter is moved by the influence of the 120 current in said coil to permit the passage of light through said opening.

8. The combination with a group of annunciator-drops, of a source of light common to all of said drops, a device for controlling said 125 source of light, and electrical connections connecting all of said drops in circuit with said controlling device.

9. The combination with a group of annunciator-drops, of a source of light common to 130 all of said drops, a local circuit in which said light is included, a relay to control said local

circuit, and electrical connections connecting all of said drops in circuit with said relay.

10. The combination with a group of an-nunciator-drops comprising each a tube, a coil 5 of wire around the tube, and a balanced shut-
ter in the field of said coil, of a source of light, common to all of said drops, a device for con-trolling said source of light, and electrical

connections including all of said coils in cir-cuit with said controlling device. 10

This specification signed and witnessed this 20th day of October, A. D. 1898.
